REFRIGERATING APPARATUS

Lawrence A. Philipp, Detroit, Mich., assignor to
 Kelvinator Corporation, Detroit, Mich., a corporation of Michigan

Application November 26, 1934, Serial No. 754,706

7 Claims. (Cl. 62—115)

My invention pertains to refrigerating systems and more particularly to refrigerating systems of the expansion type wherein the refrigerant is precooled before it enters the evaporator.

5 It is an object of my invention to provide a refrigerating system comprising a refrigerant evaporator mounted in the compartment to be cooled, and supplied with refrigerant through a high side float type expansion valve which comprises a float chamber having a float and a controlled valve therein for controlling the flow of refrigerant into the evaporator and an associated suction line connection which extends from the evaporator in heat exchange relation with the lower portion of the float chamber for precooling the liquid refrigerant in the chamber before it is discharged into the evaporator.

10 It is also an object of my invention to provide a refrigerator having a high side float type expansion valve mounted on a wall of the compartment in heat insulated relation from the compartment with a suction line connection extending from the evaporator in the compartment around the lower portion of the float chamber outside 15 of the compartment for precooling the refrigerant.

15 The invention itself, however, both as to its method of operation, together with additional objects and advantages thereof, will best be understood from the following description of specific embodiments, when read in conjunction with the accompanying drawing, in which:

20 Fig. 1 is a sectional view showing a refrigerator precooling arrangement in accordance with my invention;

25 Fig. 2 is a sectional view on line II—II thereof showing the valve actuating mechanism; and

30 Fig. 3 is an elevational view of a refrigerator, with a portion of the door broken away, showing 35 a complete refrigerator installation arranged in accordance with my invention.

35 Referring more particularly to the drawing, the apparatus comprises a high-side type float reducing valve 1 which is mounted for illustrative purpose on top of the upper heat insulating wall 3 of a compartment which is to be cooled by a refrigerant evaporator 5. The float valve comprises a cylindrical metallic shell 9 closed at its upper end and having its open lower edge hermetically secured, as by welding, to a base plate 11 which is dished to support it in spaced relation from the top wall 3 of the refrigerator. The shell 9 encloses a float chamber 12 which contains a float 13 which actuates a valve mounted on the base plate 11. The valve has its outlet connected

into a conduit 14 which extends downwardly through the heat insulating wall 3 into the evaporator 5.

40 The valve chamber shell 9 is provided with an aperture in its closed upper end to receive an inlet fixture 15 in the upper portion thereof provided with a pipe fitting 17 whereby it may be conveniently connected to a refrigerant line 18 for receiving liquefied refrigerant from any suitable source, preferably the receiver of a condenser of 45 a compressor-condenser expander type refrigerating apparatus.

45 The inlet fixture 15 is secured in the top of the shell 9 in hermetically sealed relation, in any well known manner, as by welding, and is provided with a depending bracket portion 19 which extends into the chamber. The bracket portion supports a liquid deflecting plate 21 and a screen 23 transversely in the chamber 12 for breaking up the force of the liquid refrigerant entering 50 through the channel 24 from the pipe 18, thereby minimizing its direct action upon the float 25. A vent aperture 27 extends through the inlet fixture 15 and is closed by an external cap 29 which may be removed for conveniently venting the 55 chamber when desired.

55 The float 25 in the chamber is provided with a lug 31 at its lower end which is pivotally connected to the end of a pivoted valve lever 33. The valve lever 33 is substantially channel shaped in 60 cross section, and is provided at its opposite end with a pair of spaced arms 34 extending on opposite sides of the valve casing 35, which extends upwardly through the base plate 11. A pivot pin 37 extending through the ends of the spaced arms 35 65 of the lever 33 passes loosely through a slot 39 on the side of the valve casing 35 adjacent the outer shell 9 of the float chamber.

70 A flow restricting valve 41 is slidably disposed in an orifice 43 provided in the valve casing 35 and has its lower end tapered for engaging a valve seat 45 which obstructs the lower portion of the orifice. The valve is actuated from the valve lever 33 by means of a pin 47 which extends through the valve between the spaced arms 34 of the lever 45 and moves freely in elongated slots 49 provided in the valve casing. A valve guide 51 is provided in the upper end of the orifice 43 for guiding the 75 slidable valve member.

75 The lower end of the valve casing 35 is provided with a laterally projecting flange 53 which abuts the lower surface of the base plate 11 to which it may be hermetically sealed in any suitable manner, as by welding for example. The base plate 11 of the float chamber is preferably pro- 80

vided with a downturned peripheral edge having outwardly turned pedestal portions 55 for mounting the float valve assembly 1 or any convenient flat surface.

5 The liquid refrigerant enters the float chamber 12 at a relatively high temperature, and, in order to cool it before it is discharged from the float chamber to the evaporator 5, the refrigerant vapor is drawn through conduit means disposed in intimate thermal relation with the liquid refrigerant in the bottom of the chamber. For this purpose I preferably provide a conduit 57 which is coiled about the lower edge of the float chamber shell 9 in intimate thermal coupled relation therewith.

10 For increasing the thermal coupling between the conduit 57 and the float chamber shell 9 these members are preferably secured together as by welding or soldering. The lower end of the cooling coil 57 is connected to a conduit 59 which passes through the heat insulating wall 3 of the compartment to the outlet of the evaporator 5. The other end of the cooling coil is connected to any suitable suction line 61 for drawing the refrigerant vapor from the evaporator. A quantity 15 of heat insulating material 63, is preferably provided about the lower portion of the float chamber 9 over the cooling coils 57.

15 Although the suction line 61 and the refrigerant pipe 18 from my precooled float valve may be operatively connected to any suitable system, a complete installation may be provided by arranging an adjacent compressor-condenser unit 66 on top a refrigerator 68, as shown in Fig. 3. 20 Such a unit comprises a condenser 67 associated with a compressor 69 which is driven by an electric motor 71 which may be automatically controlled by a thermostat switch or pressure device, in the usual manner, to operate the compressor for supplying the correct amount of liquefied refrigerant to the evaporator. The suction line 61 which extends from the precooling device on the float valve is connected to the low side of the compressor 69, and the high side of 25 the unit is connected from the condenser through a conduit 18 to the inlet fitting on the float valve chamber 9.

30 In operation the compressor 69 draws refrigerant vapor from the evaporator 5 through the cooling coils around the shell 9 of the high side float chamber, and forces it under high pressure through the condenser 67 where its latent heat of vaporization is dissipated thereby recondensing it. The liquefied refrigerant passes through the refrigerant line 18 into the high side float chamber 12, and when a predetermined quantity has accumulated therein the float 25 causes the valve to open to the conduit 75 thereby discharging precooled refrigerant through the compartment wall 3 into the low pressure evaporator.

35 The condensing refrigerant enters the float chamber at a relatively high temperature of substantially 120° Fahrenheit for example. Although the heat of the refrigerant liquid is slightly dissipated as it stands in the float chamber its temperature would ordinarily be well above 40 100° Fahrenheit when discharged through the valve from the high pressure side of the system to the low pressure side. When released from the high pressure side to the low pressure at such a high temperature, a large portion of the liquid refrigerant flashes at once to vapor, thereby absorbing a large quantity of heat from the refrigerant. A substantial portion of the liquefied refrigerant is thus ordinarily wasted in lowering the

temperature of the remaining portion of the liquid.

45 In accordance with my invention, however, the withdrawal of the cold refrigerant vapor from the outlet of the evaporator through the cooling coils 57 on the shell 9 of the float chamber absorbs a large portion of the excess heat from the liquid refrigerant accumulated therein before it passes through the valve. The float valve chamber 9 is relatively tall and the cooling coils 57 are so arranged thereon that they absorb heat only from the liquid in the bottom of the chamber. The refrigerant vapor which accumulates above the liquid in the chamber is at such a high temperature that the atmosphere absorbs heat directly therefrom. Passing through the coils 57 the cold refrigerant vapor drawn from the evaporator 5 is thus further utilized before it returns to the compressor 69, and the liquefied refrigerant in the float chamber 12 is cooled so that it passes 20 through the valve with but slight vaporization.

50 It will be seen that I have provided a refrigerating system comprising a precooled high-side type float reducing valve of simple and compact construction which may be conveniently installed on any refrigerator and which contributes materially to the efficient operation of the system. My precooling arrangement is especially useful with small refrigerant compressor installations, of about seven horse-power or smaller for example. 30 In small compressors the ratio of the metallic mass to the displacement volume of the piston is so high that the compressor wastes the cold vapor which absorbs a large quantity of heat from the cylinder walls.

55 Aside from the specific embodiments of the invention herein shown and described, it will be understood that numerous details of the construction may be altered or omitted without departing from the spirit and scope of the invention as disclosed and claimed, and that I do not desire to limit the invention to the exact constructions herein set forth.

60 I claim as my invention:

1. In a refrigerating system including a compartment to be cooled, and an evaporator for cooling said compartment, the combination of a flow controlling device adapted to be mounted external to said compartment, said device comprising a float chamber, a float and a valve in said chamber, conduit means for conducting refrigerant from said valve to said evaporator, a suction line for withdrawing refrigerant vapor from said evaporator including a conduit disposed in intimate thermal relation with the liquid refrigerant in the lower portion only of the float chamber, and heat insulation for the lower part of said float chamber.

65 2. In a refrigerating system including a compartment to be cooled, and an evaporator for cooling said compartment, the combination of a flow controlling device adapted to be mounted external to said compartment, said device comprising a float chamber, a float and a valve in said chamber, conduit means for conducting refrigerant from said valve to said evaporator, a suction line for withdrawing refrigerant vapor from said evaporator including a conduit disposed in intimate thermal relation around the lower portion only of said float chamber, and heat insulation material disposed around said lower portion of the float chamber over said conduit.

70 3. In a refrigerating system including a compartment to be cooled, an evaporator mounted in said compartment, the combination of a flow con-

trolling device, a chamber for storing a quantity of liquid refrigerant on the supply side of said flow controlling device, and means for cooling the lower part of the stored liquid comprising a 5 suction line connection for drawing refrigerant vapor from said evaporator in closed coupled thermal relation with the lower part only of said chamber.

4. In a refrigerating system including a compartment to be cooled, an evaporator mounted in said compartment, the combination of a valve 10 for controlling the flow of refrigerant into said evaporator, means for controlling the actuation of said valve comprising a float chamber for receiving refrigerant, and means responsive to the quantity of refrigerant therein, and means for cooling the lower part of the liquid refrigerant in said chamber comprising a suction line connection for drawing the refrigerant vapor from 15 said evaporator in closed coupled thermal relation around the lower part only of said chamber.

5. A refrigerant flow controlling device comprising a float chamber, a valve in said chamber, a float therein, a float controlled mechanism in

said chamber for actuating said valve, and a conduit disposed in intimate thermal coupled relation adjacent the lower portion only of said float chamber.

6. A refrigerant flow controlling device comprising a float chamber, a valve in said chamber, a float therein, a float controlled mechanism in said chamber for actuating said valve, a conduit coiled about the lower portion of said float chamber in intimate thermal engagement therewith 10 and heat insulating material on the lower portion only of said chamber over said conduit.

7. A refrigerant flow controlling device comprising a float chamber, enclosed by a cylindrical shell open at one end, a base plate secured in 15 the open end of said shell, a float in said chamber, a valve mounted in said base plate, a float controlled mechanism for actuating said valve, a conduit coiled about the lower portion only of said shell in intimate thermal engagement there- 20 with, and heat insulating material on the lower portion of said shell over said conduit.
